UNITED STATES PATENT OFFICE.

GIULIO SILVESTRI, OF VIENNA, AUSTRIA-HUNGARY.

MOTOR WITH ROTATING PISTON

SPECIFICATION forming part of Letters Patent No. 728,630, dated May 19, 1903.

Application filed February 26, 1902. Serial No. 95,787. (No model.)

To all whom it may concern:

Be it known that I, GIULIO SILVESTRI, a citizen of Austria, residing at Vienna, in the Province of Lower Austria, Austria-Hungary, have invented certain new and useful Improvements in Rotary Engines, of which the following is a specification.

This invention relates to motors with rotary pistons of that class in which the radial outward movement of the slides of the rotary piston is effected by the motor fluid itself and in which the slides are guided in special guide-planes arranged in the cylinder-casing bore. It has been found in engines of this character that the springs used to press the slides of the rotary piston in radial outward direction would, due to the effect of the steam and heat, deteriorate, and so be impaired in their effectiveness.

20 The object of this invention is to do away with the springs and with the disadvantages accompanying the same and also to provide means whereby a movement of the slides is produced without the objectionable shocks attendant many of the engines hitherto in use when passing the abutments; and for this purpose the invention consists of a rotary engine having a cylinder-casing provided with inlet and exhaust ports and bearings, a hollow shaft in said bearings, a piston on said shaft rotatable in the cylinder-casing and provided with radial recesses, slides in said radial recesses, sliding pistons also in said radial recesses adapted to be moved by the motor fluid entering the hollow shaft for forcing the slides outwardly against the casing-bore, adjustable spring-actuated abutments in recesses of the casing-bore, and packing-strips on the ends of the abutments provided with elastic extensions the ends of which bear in recesses of the casing-bore, so as to be flush with the same, while the extensions are of a curvature corresponding to an osculating circle of the circle of the casing-bore, as will be described more fully herein-after and finally pointed out in the claim.

In the accompanying drawings, Figure 1 is a longitudinal section on line A B of Fig. 3. Fig. 2 is a longitudinal section on line C D of Fig. 3. Fig. 3 is a vertical transverse section on line E F of Fig. 1, and Fig. 4 shows

partly a section on line G H of Fig. 1 and partly the cover of the casing in elevation.

Similar letters of reference indicate corresponding parts.

55 Referring to the drawings, *a* represents the casing of the rotary engine, provided with inlet and exhaust ports and bearings and in which casing the piston *b* is centered in such a manner that between the piston *b* and the wall of the casing *a* an annular passage *c* is formed, which is interrupted at one or more points by abutments *f*.

The piston *b* is provided with radial recesses in which are guided slides *d*. The abutments are guided in recesses of the cylinder-casing *a* and protrude beyond the same radially inwardly into the annular passage *c*. Fixed on the inner side of each abutment is a metal plate or packing-strip *g*, provided with extensions *m*, passing to recesses *h* of the casing-bore, so as to be flush with the same and of such curvature as to correspond to a circle which osculates on the circle of the casing-bore. The elastic ends *m* of the packing-strips *g* bear on the casing-wall and form guides for the movement of the slides *d* in the recesses of the rotary piston, whereby, due to the special curvature of the guides, a shockless movement 70 of the slides is accomplished. No matter how the abutments *f* are adjusted the extensions *m* will always bear with their ends in the recesses of the casing-bore, and so always provide an obstructionless and proportionately smooth passage to the slides *d*. Heretofore the guide-plane, which regulates the radial movement of the slides, had always a circular form and was determined by the intersection of the guide-circle with the circle of the casing-bore. This curvature caused the action of the slides to be accompanied by shocks. A shockless passage of the slides requires such a form of guide-plane as to cause the follower or slide to be first equally accelerated and then equally retarded. The directrix which regulates this movement is characterized thereby that its ends are tangent to the circle of the casing-bore. Therefore the guide-planes correspond to osculating circles 85 of the casing-bore, whereby a raising and lowering of the slides unaccompanied by the

objectionable shocks is accomplished. The abutments *f* are pressed against the rotary piston *b* by means of springs *k*, which are interposed between flanged bolts *i* and screws *q* in the casing-wall *a*. By means of the screws *q* the tension of the springs *k*, and thereby also the pressure of the abutments on the rotary piston, can be regulated. The shaft *n*, which is attached to the rotary piston *b*, is provided with a recess *o*, which is connected with the supply of motor fluid. The central part of the shaft is provided with radial recesses for sliding pistons *p*, which pass radially outwardly into the recesses of the rotary piston guiding the slides *d* and are so arranged as to press the slides *d* in outward direction when the sliding pistons *p* are acted upon by the motor fluid entering the hollow shaft *n*. By the arrangement of the parts the pistons *p* and slides *d* are equally pressed against the casing-bore and abutments. By means of these sliding pistons the use of springs is obviated.

It has been found in engines with rotary pistons that the casing is deformed, so that the slides at some points press closely against the casing-bore, while at other points there are spaces between the slides and the casing-bore. This inequality caused leakage, and therefore a poor utilization of the motor-power. For this reason I propose to make the casing-walls abnormally thick, at least equal to or larger than the half radius of the casing-bore, and to provide ribs on the casing to strengthen the same, which enable the casing to resist the high variable radial pressure without damage, whereas to reduce the weight holes are arranged in the walls. In the place

of steam any other motor fluid—as compressed air, steam, and the like—may be used, and the passages for admission and exhaust of the motor fluid may be provided on the inside or outside of the casing-wall. The rotary engine may also be used as a pump, in which case a belt or coupling with a motor is provided.

Having now described my invention, I claim as new and desire to secure by Letters Patent—

In a rotary engine, the combination, of a cylinder-casing provided with inlet and exhaust ports and bearings, a hollow shaft in said bearings and radial recesses in said shaft, a piston on said shaft rotatable in the cylinder-casing and provided with radial recesses, slides in said radial recesses of the piston, sliding pistons in the recesses of the shaft and recesses of the piston, and adapted to be moved by the motor fluid entering the hollow shaft radially outwardly against the slides, adjustable spring-actuated abutments in recesses of the cylinder-casing bore, and packing-strips on the ends of the abutments provided with elastic extensions, the ends of which bear in recesses of the casing-bore, so as to be flush with the same, while the extensions are of a curvature corresponding to an osculating circle of the circle of the casing-bore, substantially as set forth.

In testimony that I claim the foregoing as my invention I have signed my name in presence of two subscribing witnesses.

GIULIO SILVESTRI.
